UNITED STATES PATENT OFFICE.

HENRY HEYWOOD AND DAVID F. PRATT, OF GARDNER, MASSACHUSETTS.

DIE FOR CUTTING RATTAN.

SPECIFICATION forming part of Letters Patent No. 311,658, dated February 3, 1885.

Application filed November 19, 1884. (No model.)

To all whom it may concern:

Be it known that we, HENRY HEYWOOD and DAVID F. PRATT, of Gardner, in the county of Worcester and State of Massachusetts, have invented a new and Improved Machine for Working Rattan, of which the following is a full, clear, and exact description.

Our invention relates to improvements in dies for splitting rattan into several sticks or reeds; and to this end it consists in a die of peculiar construction, as will be hereinafter fully described, and pointed out in the claim.

Reference is to be had to the accompanying drawings, forming part of this specification, in which similar letters of reference indicate corresponding parts in all the figures.

Figure 1 is a plan view of our improved machine for working rattan. Fig. 2 is a central sectional view of the same. Fig. 3 is a front end view of the improved die. Fig. 4 is a cross-sectional view of the same on the line $x-x$, Fig. 2. Fig. 5 is a side view of the rattan partly split.

In our improved machine we use a die, A, which is held on a suitable platform, B. Feed-rollers C, having a single groove in the periphery, are arranged in pairs in front of the die, and rollers D, having several grooves in the periphery, are arranged behind it, all the rollers being driven by cog-wheels or other devices, as in other rattan-machines. The die A is provided with two or more bores, a, parallel with each other, and of the diameter of the desired reeds. The front ends of the sides of the bores are tapered and sharpened to form sharp cutting-edges, so as to cut through the rattan-stick very easily. On the sides of the die two or more longitudinal ridges, F, are arranged, which have their front ends tapered and sharpened to form cutting-edges. The rear part of the die is made tubular and provided

with a single bore, G, and the inner ends of the grooves or recesses between the ridges F are tured outward. In the drawings we have shown five small bores, a, and four ridges, F; but the number of each may be varied as may be desired. The number of grooves b in the rollers D is the same as the number of bores a in the die A. The rattan-stick H is placed between the feed-rollers C, which carry it in the direction of the arrow a', and force its ends against the front end of the die. The sharp cutting-edge of the bores a and the ridges F split the rattan-stick into as many pieces as there are bores and ridges. The outer parts, J, are bent outward and from each other, and the inner parts or reeds, K, pass through the bores a. The outer parts, J, are forced off the sides of the platform, and the reeds K are seized by the grooved rollers D and pulled through the machine, thus assisting the feed-rollers C in forcing the stick through the die. As the bores a are round, the reeds K will also be round. The reeds can be made with any desired diameter or cross-section, and the rattan stick is split and the reeds formed in a single operation and by means of a single die or cutter.

Having thus described our invention, we claim as new and desire to secure by Letters Patent—

An improved die for splitting rattan, having a series of bores, a, at one end, and a single larger bore, G, at the other end, and provided with two or more longitudinal splitting-ridges, F, on the outside, substantially as shown and described.

HENRY HEYWOOD.
DAVID F. PRATT.
